UNITED STATES PATENT OFFICE.

JENS GABRIEL FREDRIK LUND, OF CHRISTIANIA, NORWAY.

ARMED BUILDING-STONE.

No. 802,223.

Specification of Letters Patent.

Patented Oct. 17, 1905.

Application filed February 23, 1905. Serial No. 246,855.

To all whom it may concern:

Be it known that I, JENS GABRIEL FREDRIK LUND, engineer, a citizen of Norway, residing at Björn Farmandsgade 2, in the city of 5 Christiania, Norway, have invented new and useful Improvements in Armed Building-Stone, of which the following is a specification.

The armed constructions of concrete hitherto used may be divided in two main groups. To the first one may, for instance, be reckoned the systems Hennebique, Monier, &c. The characteristic feature of this first group is that the floor is cast at the building-place. 15 This is for certain purposes very suitable; but it is followed by the great inconvenience that heavy and costly scaffolds must be used. Besides, the material is badly utilized, as the section is compact, and on account hereof the 20 construction is very little sound-deadening and heat-insulating. The second main group is characterized, for instance, by system Siegwart, in which the building parts are produced in a manufactory way. Here the advantage 25 of an economical utilization of material, &c., is present; but it is necessary to work with big and heavy building parts.

My present invention has for its object to avoid the disadvantages and to obtain the advantages of both groups. For this purpose 30 the construction is built up by single hollow artificial stones provided with tongues and grooves in the direction perpendicular to the supports, and which stones are individually 35 armed in the direction parallel to the supports, whereby the material may be easily placed far from the neutral axis.

The invention is illustrated in the accompanying drawings, in which—

40 Figure 1 is a cross-sectional view of a building-stone which is armed in accordance with my present invention. Fig. 2 is longitudinal section of the stone. Figs. 3 and 4 are two views of a building construction seen from two directions perpendicular to each other and made by singly-armed artificial stones. 45 Fig. 5 is a cross-sectional view along the line *a b* in Fig. 3. Figs. 6 and 7, 8 and 9, 10 and 11 are central longitudinal sections and plan 50 views, respectively, showing a second, third, and fourth form of execution of the arming. Figs. 3 and 4 may represent a part of a wall or a floor. The stones provided with

tongue and groove are placed in such a manner between the supports 1 and 2 that the 55 stones of each row form a continuous tongue, which engage the corresponding continuous groove formed by the neighboring row. When, therefore, the joints 3 are arranged in bond, the floor or wall will be very resistant 60 against loads in vertical, respectively in horizontal direction. The stresses caused by the loads are transferred only through the stone tongues 4 or groove projections 5 to the adjacent stones and from these latter further to 65 both supports. The problem is here now to construct a stone which in consisting of a minimum quantity of material is able to resist these stresses. In the groove projections 5 and tongues 4 shearing stresses are caused exclusively or to a predominant extent. The 70 main flanges 8, however, also receive tension and compression. The question consequently is to arm the stones in such a manner that the stone mass in connection with the irons embedded therein are able to resist these stresses, at the same time as all material is arranged as 75 distant as possible from the axis of centers of gravity of the stones. This problem may be suitably solved in the manner shown in Figs. 1 and 2. In the mass iron bands 6 and 7 are embedded alternately. The band 6 goes from the under part of the tongue 4 in an inclined direction upward through the tongue and through the upper part of one of the side walls 9, further through the upper main flange 8, then down through the other side wall 10, and at last in inclined direction to a point near the under side of the lower groove projection 5. (See 80 the full lines in Fig. 1.) The next band 7, 85 however, goes from the upper part of the tongue 4 in an inclined direction downward through the tongue and through the lower part of the wall 9, further through the lower main flange 8, then up through the other side wall 10, and at last in inclined direction to a point near the upper side of the upper groove projection 5. (See the dotted lines in Fig. 1.) The next band 100 2, however, goes from the upper part of the tongue 4 in an inclined direction downward through the tongue and through the lower part of the wall 9, further through the lower main flange 8, then up through the other side wall 10, and at last in inclined direction to a point near the upper side of the upper groove projection 5. (See the dotted lines in Fig. 1.) In this manner the successive bands are alternately arranged, as clearly shown in Fig. 2. The distance between the bands may be made, for instance, equal to the double band width. Instead of bands wires of iron may be used. It is seen without further description 105 that the shearing stresses, which appear in the tongue 4 or the groove projections 5, will

as tension in one set of iron bands be transferred to the main flanges 8. At the same time the flanges 8 are stayed against the appearing tension, while the compression is taken up by the concrete mass directly. It also will be understood that the material in this manner may be placed as far out as possible, whereby the best utilization is obtained. The whole construction becomes a small weight and fixed scaffolds are not necessary for the mounting. Only displaceable plates are required, because the stones will carry themselves when three rows are mounted.

In the arrangement shown in Fig. 2 there are, between the bands, parts of the mass in which no bands are present. Although this is of small importance, it may easily be prevented, for instance, in the manner shown in Figs. 6 and 7, in which all upper iron parts (shown as wires or rods) are arranged aslope one way and the lower ones arranged aslope the other way. Hereby a certain rigidity is obtained in the longitudinal direction of the stone. In Figs. 7, 9, and 11 the upper parts of the irons are illustrated by thick lines, while the lower parts are drawn by thin lines. This binding together in longitudinal direction is still more perfected in Figs. 8 and 9, in which the irons consist of "expanded metal," which forms a continuous net. In this case one piece of expanded metal may be used for each set of irons, and these two pieces, the widths of which correspond to the complete length of each band in Fig. 1, are cut and bent in such a manner that one of them forms two sets of sloping iron parts, crossing each other and replacing the upper bands 6, while the other piece replaces the bands 7. The junction-points are preferably arranged at the middle of the flanges 8, and in order that the parts may clear each other both pieces are displaced a half-pitch in relation to each other, as shown in Figs. 8 and 9.

It is seen that in all preceding constructions the upper parts 6 are not connected with the lower parts 7. This may, however, be accomplished by means of a single continuous wire, as shown in Figs. 10 and 11. Here every second crossing part 11 is bent upward and every second part 12 is bent down, as it is clearly seen by means of the thick and thin lines. The whole arming skeleton in this manner forms one single piece. The parts corresponding to the bands 6 are 17 18 11 19 20 and those corresponding to the bands 7 are 13 14 12 15 16. (See also Fig. 7.)

Having now described my invention, what I claim as new, and desire to secure by Letters Patent, is—

1. A cast or pressed artificial-stone block, having an edge rib along one longitudinal edge, and an edge groove along the other longitudinal edge, and having within its mass a number of metal bands or wires which are arranged alternately in such a manner that one band extends from the under part of the edge rib through the upper main flange to the lower groove projection, while the next band extends from the upper part of the edge rib through the lower main flange to the upper groove projection. 60

2. A cast or pressed artificial-stone block, having an edge rib along one longitudinal edge, and an edge groove along the other longitudinal edge, and having within its mass sets of metal bands or wires, which are arranged alternately in such a manner that one set of bands sloping in one direction extend from the under part of the edge rib through the upper main flange to the lower groove 75 projection, while the next set of bands, sloping in an opposite direction, extend from the upper part of the edge rib through the lower main flange to the upper groove projection. 80

3. A cast or pressed artificial-stone block, 85 having an edge rib along one longitudinal edge, and an edge groove along the other longitudinal edge, and having within its mass net-like metal bands or wires having overlapping parts and which are arranged alternately 90 in such a manner that one band extends from the under part of the edge rib through the upper main flange to the lower groove projection, while the next band extends from the upper part of the edge rib through the lower 95 main flange to the upper groove projection.

4. A cast or pressed artificial-stone block, having an edge rib along one longitudinal edge, and an edge groove along the other longitudinal edge and having within its mass 100 net-like metal bands or wires having overlapping parts, and constituting a cage, which passes through the edge rib, and through the upper and lower main flanges of the block.

In testimony whereof I have signed my name 105 to this specification in the presence of two subscribing witnesses.

JENS GABRIEL FREDRIK LUND.
